A. H. PEYCKE,
REVERSIBLE FULCRUM AND METHOD OF MAKING SAME.
APPLICATION FILED MAR. 20, 1920.

UNITED STATES PATENT OFFICE.

ARMAND H. PEYCKE, OF CHICAGO, ILLINOIS, ASSIGNOR TO AMERICAN STEEL FOUNDRIES, OF CHICAGO, ILLINOIS, A CORPORATION OF NEW JERSEY.

REVERSIBLE FULCRUM AND METHOD OF MAKING SAME.

1,405,801.

Specification of Letters Patent.

Patented Feb. 7, 1922.

Application filed March 20, 1920. Serial No. 367,369.

To all whom it may concern:

Be it known that I, ARMAND H. PEYCKE, a citizen of the United States, residing at Chicago, in the county of Cook and State of Illinois, have invented certain new and useful Improvements in Reversible Fulcrums and Methods of Making Same, of which the following is a specification.

This invention relates to an improvement in reversible fulcrums and method of making same.

The objects of this invention are to provide a simple and improved reversible fulcrum and a simple and improved method of making the same.

These and other objects are accomplished by means of the arrangement disclosed on the accompanying sheet of drawings, in which—

20 Figure 1 is a plan view of a reversible fulcrum embodying my invention and disclosing the method by which same is formed;

Figure 2 is a side elevation of the same fulcrum; and

25 Figure 3 is a sectional view taken in the plane of line 3—3 of Figure 2.

The various novel features of the invention will be apparent from the following description and drawings, and will be particularly pointed out in the following claims.

Referring to the figures of the drawings, it will be noted that I have provided a fulcrum consisting primarily of three main parts, 10, 11 and 12, the part 10 being the 35 lever supporting member, the part 11 being an intermediate support embracing the lever supporting member 10, and the part 12 being the strut which embraces the intermediate support 11. The intermediate support 40 11 preferably, and as shown, is in the form of an endless band.

The lever receiving member 10 is first formed, either by casting or forging, and has a slot 13 for receiving the lever, and also 45 has trunnion portions 14 and 15, whereby the fulcrum is reversible. The intermediate support 11 is next formed around the lever supporting member 10. This intermediate support 11 may be forged around the member 10 or cast around the same. In the latter case, the lever supporting member 10 will act as a core, as described in my copending application, Serial No. 367,367, filed March 20, 1920, the surfaces of said lever support-

ing member being provided with some suitable parting medium, such as shellac, to prevent the adherence of molten metal.

In forming the intermediate support 11, the same is provided with trunnion receiving portions 16 and 17 to rotatably receive 60 the trunnions 14 and 15 respectively of the lever supporting member 10. Also, the intermediate support has its sides or legs provided with concave portions 18 to loosely receive the lever supporting member, as shown particularly in Figure 3. This intermediate support 11 also is provided with flanges 19, between which are received the sides or legs of the strut 12, the strut preferably being of forged metal and bent 70 around the intermediate support, after having been provided with a tension rod seat 20, and having the rear ends 21 and the legs bent laterally for attachment to the compression member of the brake beam.

To secure the lever supporting member 10 in various adjusted positions, I have provided the trunnion portion 15 with three slots, 22, 23 and 24, which may receive a key 25 for locking purposes. By providing three 80 slots in the trunnion portion 15 of the lever supporting member, the lever receiving slot 13 may take a lever at the usual forty degrees to either side of a vertical position, or take the lever in a vertical position to meet 85 all operating conditions.

It is my intention to cover all modifications of the invention falling within the spirit and scope of the following claims.

I claim:

1. A reversible fulcrum, comprising a lever supporting member, an intermediate support in which said member is rotatably mounted, and a strut formed around said intermediate support.

2. A reversible fulcrum, comprising a lever supporting member having trunnions formed on the end thereof, an intermediate support having trunnion receiving portions whereby the lever supporting member is rotatably mounted in said intermediate support, and a strut embracing said intermediate support.

3. A reversible fulcrum, comprising a lever supporting member, an endless band embracing said member for supporting the same, and a strut formed around said band for supporting the latter.

4. A reversible fulcrum, comprising a lever supporting member, an intermediate support in which said member is rotatably mounted, said intermediate support having 5 flanges, and a strut formed around said intermediate support and being located intermediate said flanges.
5. A reversible fulcrum, comprising a lever supporting member, an intermediate 10 support in which said member is rotatably mounted, a strut formed around said intermediate support, and means for locking said lever supporting member in a given position within said intermediate member.
15. 6. A reversible fulcrum, comprising a lever supporting member, an intermediate support in which said member is rotatably mounted, a strut formed around said intermediate support, and means for locking said

lever supporting member in a plurality of 20 positions within said intermediate member.

7. The method of making a reversible fulcrum, consisting first in forming a lever supporting member, then forming an intermediate support around said member, and 25 then forming a strut around said intermediate support.

8. The method of making a reversible fulcrum, consisting first in forming a lever supporting member with trunnions, then forming an intermediate support around said member with trunnion receiving portions, 30 and then forming a strut around said intermediate support.

Signed at Chicago, Illinois, this 27th day 35 of February, 1920.

ARMAND H. PEYCKE.
